CALENDAR WATCH MOVEMENT

Hans Aeberhardt, Bienne, Switzerland

Application December 16, 1936, Serial No. 116,205
In Switzerland December 17, 1935

4 Claims. (Cl. 58—58)

The present invention relates to a calendar watch movement.

The watches of this kind, known heretofore, have a mechanism by which the calendar index indicates the date by jumping one step every 24 hours. To effect this a spring is required which by reason of a poor hardening of the steel or of fatigue on account of insufficient hardening makes frequent repairs necessary.

The movement according to the present invention avoids such deficiencies. The mechanism is constituted only of gear wheels and pinions and the index wheel has a continuous rotating movement and may be arranged either centrally, that is, on the center pivot staff, or eccentrically on a pivot which may be provided for instance on the head of the fastening screw of the cock of the time setting mechanism.

A particular advantage of the watch movement arrangements according to the present invention besides those already mentioned is the fact that watchmakers who are manufacturing different patterns of calendar watches, as for instance such with a calendar dial arranged concentrically to the ordinary time dial and such with separate calendar dials, need to keep in stock only a single standard pattern of spare plates, instead of providing as many stocks of plates as there are different patterns to be made. This saves much money especially also owing to the fact that only a single controlling and verifying punch which is very expensive is required.

In the annexed drawings several embodiments of the invention are represented schematically.

Figures 1 and 2 are two plan views showing that the calendar wheel may be arranged centrally as in Fig. 2 or eccentrically on a pivot arranged coaxially with the wheel of the time setting mechanism;

Fig. 1a is a sectional view on a line Ia—Ia of Fig. 1;

Fig. 2a is a sectional view on the line IIa—IIa of Fig. 2;

Figs. 3 and 4 are two plan views showing arrangements where the calendar wheel may be mounted either centrally or eccentrically on an optional radial line;

Fig. 3a is a sectional view on line IIIa—IIIa of Fig. 3;

Fig. 4a is a sectional view on line IVa—IVa of Fig. 4;

Fig. 5 is a sectional view similar to that of Fig. 3a but having the calendar wheel arranged below instead of above the intermediate wheel,

whereby the watch may be reduced somewhat in thickness;

Fig. 6 is a sectional view similar to that of Fig. 2a but having the calendar wheel arranged above the dial;

Figs. 7, 8 and 9 show arrangements similar to those of Figs. 1 and 2 permitting the placing of the calendar wheel centrally or eccentrically but so that the diameter of the watch may be reduced as for wrist watches;

Fig. 8 is a sectional view on a diameter including the pivot of the second hand; and

Figs. 10 and 11 are views of dials, Fig. 10 of the arrangements in Figs. 1 and 9 and Fig. 11 of the arrangements in Figs. 2, 4 and 7.

The gear wheels used in most all these embodiments of the invention consist of a gear wheel having a pinion formed at its hub.

According to Figs. 1 and 1a where the latter is a section on the line Ia—Ia of Fig. 1, the pinion 2 integral with the minute cannon 3 mounted on the center staff 1 meshes with an intermediate wheel 5 pivoted on 4. The pinion 6 of wheel 5 meshes on one side with hour wheel 8, integral with the hour wheel sleeve 7, and on the other side with an intermediate wheel 10 pivoted on pivot pin 9 and meshing with its pinion 11 with an intermediate wheel 13 pivoted on pivot 12. The pinion 14 of this wheel operates the calendar wheel 15, which is pivoted on a pin 17 arranged coaxially with the pivot of an intermediate wheel 16 of the time setting mechanism, which is located in a notch 18 of the plate and meshes by a second intermediate wheel 19 with the intermediate wheel 5 pivoted on pin 4.

Instead of the eccentric arrangement, as just described, the calendar wheel 15' could also be mounted by a centric arrangement on the hour wheel sleeve 7 as shown in Figs. 2, 2a, where the latter is a section on the line IIa—IIa in Fig. 2. Pinion 14 of the intermediate wheel 13 is in this case located at the same distance from pivot 1 as from pivot 17 which is fast to and projecting from the center of the screw head 17a.

The calendar wheel could also be located as shown in Figs. 3, 3a, where the latter is a section on the line IIIa—IIIa in Fig. 3.

In this arrangement the hour wheel sleeve 7 carries besides the hour wheel 8 a pinion 20 which meshes with an intermediate wheel 22 pivoted on pin 21. The pinion 23 of this wheel 22 meshes according to Fig. 3 with the calendar wheel 15'' on pivot pin 24. Now since the distances between pivot 1 and pivot 21 and between 21 and 24 have been chosen the same the calendar

wheel could also be mounted concentrically to the center pivot pin 1. The advantage of these arrangements represented in Figs. 3, 3a, 4, 4a is that only one intermediate wheel 22 is needed. In Figures 4 and 4a the calendar wheel 15² projects with its sleeve to the outside of the dial where it carries a hand 35 as shown in Fig. 11. In Fig. 6, there is also represented on the left-hand side a changed arrangement of intermediate wheel 13', and in Fig. 5, which is a modified arrangement of Fig. 3a, on the right-hand side a changed arrangement of the intermediate wheel 22. In the first of these arrangements (Fig. 6), the intermediate wheel 13' pierces with its pinion the dial to mesh with the calendar wheel, and in the second arrangement (Fig. 5), the intermediate wheel 22 is placed above, instead of beneath, the corresponding calendar wheel to permit reducing of the thickness of the watch. In the embodiment according to Figs. 7, 8 and 9, where Fig. 8 is a section of Fig. 7, the pinion 2 of the minute cannon 3 supported by the center pivot 1 meshes with an intermediate wheel 5 pivoted on pin 4 and the pinion 6 of this wheel meshes on one side with the hour wheel 8 and on the other side with a wheel 26 pivoted on pin 25. The pinion 24⁰ of this latter wheel engages the wheel 29 pivoted on pin 28 and the pinion 27 of this wheel engages the centrally arranged calendar wheel 30 but could also as shown in Fig. 9 operate an eccentrically arranged calendar wheel 30' which is pivoted on an extension 32 of a fastening screw 17⁰ of the cock 33 of the time setting mechanism. This is made possible by the fact that the distances between pivot 28 and the pivots 1 and 32 have been chosen the same. Pivot 1 carries the calendar wheel 30 inside of the dial 34, which wheel projects with its hub to the outside of the dial and carries there the index 35. The time setting mechanism is located within a notch 36 of the plate 31. The hour-hand is marked with 38, the minute-hand with 39 and the second-hand with 40.

The increased space required by the calendar mechanism is easily obtained by sinkings in the plate.

From Fig. 1a it is seen, that plate 31 has sinkings for the single parts of the calendar mechanism while according to Fig. 8 there is one whole sinking which leaves only a narrow rim 41 surrounding the mechanism.

Fig. 10 shows a front view of a watch with an eccentrically arranged calendar wheel and Fig. 11 a front view of a watch with a concentric arrangement of a calendar wheel.

What I claim as new is:

1. In a calendar watch movement and in combination, a center staff, an hour wheel sleeve, a pinion provided thereon, an auxiliary pivot,

a calendar wheel mounted thereon, one intermediate gear consisting of a spur wheel and a pinion adapted to transmit the movement from the hour wheel sleeve to the calendar wheel, the distance between the center staff and the pivot 5 of the intermediate gear and between this pivot and the auxiliary pivot being the same.

2. In a calendar watch movement and in combination, a gear wheel mechanism comprising a center staff, an hour wheel sleeve and an hour 10 wheel, two optional pivots capable of receiving a calendar wheel, one of said pivots being concentric with the center staff and the other pivot being auxiliary and eccentric thereto, a calendar wheel with index on one of said pivots, and an 15 additional gear wheel mechanism to transmit movement from the hour wheel sleeve to said calendar wheel.

3. In a calendar watch movement and in combination, a gear wheel mechanism comprising a 20 center staff, an hour wheel sleeve and an hour wheel, a time setting mechanism, a screw head on said time setting mechanism formed as an auxiliary pivot of the movement and adapted to receive a calendar wheel, a calendar wheel 25 mounted on said hour wheel sleeve, an intermediate pivot having a gear mounted thereon and consisting of a spur wheel and a pinion, said pinion meshing with the calendar wheel, said pivot pin being located at the same distance 30 from said auxiliary pivot and from the center staff, and two intermeshing intermediate gears 35 consisting each of a spur wheel and a pinion and adapted to transmit movement from the hour wheel sleeve to said intermediate pinion.

4. In a calendar watch movement and in combination, a gear wheel mechanism comprising a center staff, an hour wheel sleeve and an hour 40 wheel, a calendar wheel mounted on the hour wheel sleeve, a time setting gear comprising a cock and a fastening screw, an extension formed on said screw to constitute an auxiliary pivot adapted to receive at option said calendar wheel, a wheel held by said cock coaxially with said auxiliary pivot, an intermediate gear consisting of a spur wheel and a pinion, the spur wheel 45 meshing with the wheel held by said cock and the pinion with the hour wheel, an intermediate pivot equally distant from the center staff and said auxiliary pivot, and two other intermeshing 50 intermediate gears each consisting of a spur wheel and a pinion, the first of said other intermediate gears being mounted on said intermediate pivot and having its pinion in mesh with the calendar wheel, and the spur wheel of the second of said other intermediate gears being in 55 mesh with said pinion of the first mentioned intermediate gear in mesh with the hour wheel.

HANS AEBERHARDT.
